AIR CONDITIONING UNIT

Bernard W. Jewell, Dayton, Ohio, assignor to
 Chrysler Corporation, Detroit, Mich., a corpora-
 tion of Delaware

Application November 13, 1939, Serial No. 303,969

6 Claims. (Cl. 62—140)

My present invention relates to air conditioning units, in particular air conditioning units of the compressor-condenser-evaporator type having provision for air cooling of the refrigerant in the condenser. The invention is particularly adapted to a unit of the type which is to be mounted on a window sill or in an opening in a wall of the room to be conditioned.

An object of the invention is to provide a compact arrangement of the mechanism whereby a single motor drives the compressor, a blower for producing a stream of air in thermal exchange with the condenser, and a second blower for producing a stream of air to be conditioned in thermal exchange with the evaporator.

It is a further object of the invention to provide means whereby different speeds of operation of the two blowers may be obtained with the use of a single motor and without the use of complicated and expensive reduction gearing or other speed altering devices, the two speeds being accomplished through the use of simple belts and pulleys mounted in a convenient, inexpensive and simple arrangement.

The foregoing and other objects and advantages of the present invention will be readily apparent from a study of the following specification taken in connection with the accompanying drawings wherein like numerals refer to like parts throughout.

In the drawings,

Fig. 1 is a front view of the unit of the present invention as mounted in a window, the evaporator or interior end of the unit being referred to as the front;

Fig. 2 is a side view of the unit mounted in a window;

Fig. 3 is an enlarged top plan view with the cover and other parts broken away to show details;

Fig. 4 is a vertical section of the unit taken substantially along line 4—4 of Fig. 3;

Fig. 5 is a partial horizontal section on an enlarged scale of a part of the unit taken substantially along line 5—5 of Fig. 2; and,

Fig. 6 is a partial vertical section of the unit taken substantially along line 6—6 of Fig. 4.

The unit of the present invention comprises a self-contained structure which is adapted to be mounted on a window ledge 12 and retained thereon by lowering the window sash 13 into sash retaining means 14 and 15 mounted on top of the unit, the unit being provided with a bracket 16 which may be fastened or at least abutted against the outer edge of the window sill 12 and

5 a clamping bracket 17 which may be fastened to a portion of the wall. The unit comprises an outer condensing compartment 20 in communication with the outdoor atmosphere and an inner evaporating compartment 21 in communication with the room to be conditioned. Since the unit is preferably made narrow enough to fit most windows it may be provided with lateral wings 22 and 23 to block the openings between the sides of the unit and the sides of the window in case the window is wider than the unit. The wings 22 and 23 preferably extend from substantially the midpoint of the length of the unit or beyond an insulated partition 25 dividing the condensing compartment 20 from the evaporating compartment 21 so that approximately two-thirds of the condensing compartment is beyond the plane of the window or wall, and approximately one-third thereof is inside of the plane of the window or wall.

10 The unit comprises a bottom pan 26 of heavy gauge metal which is provided with a continuous flange 27 so that any moisture which happens to collect in the bottom pan may be retained therein. The bracket 16 is preferably welded to the outer surface of the pan 26 to form a stiffening member therefor, and the pan may be provided with intruded ridges 28 and 29 which also help to stiffen and brace the unit. A mounting plate 30 is supported in the condensing compartment and provides adjustable mounting means for the driving motor 31 and the compressor 32, the motor 31 being preferably fixedly mounted on the plate 30 and the compressor 32 being preferably attached to the plate 30 by bolts extending through slots 33 by means of which the distance between the compressor and the motor may be varied. The motor 31 is provided with a double-ended shaft 34 extending longitudinally of the unit or from front to rear thereof, and the compressor 32 is preferably provided with a crank-shaft 35 substantially parallel to the motor shaft 34. The mounting plate 30 is preferably provided with depending feet 37 which are so shaped as to provide seats for springs 38 which resiliently support the mounting plate and the apparatus mounted thereon. The springs rest upon the bottom pan 26 and are retained in position by intruded lugs 39 which extend above the bottom of the pan so that any water therein can not escape through a central opening in each lug through which bolts 40 may be passed into central threaded openings in the feet 37. The bolts 40 may be rotated to draw the feet 37 against the lugs 39 so as to maintain the appa-

ratus in position during shipment of the unit, and may be loosened or removed in order that the apparatus may be yieldably supported by the springs 38 during operation thereof. The springs 38 prevent the transmission of noises and vibrations from the motor, compressor, and blowers to the remainder of the unit, and the unit may be mounted on a resilient pad 41, and the clamping members 14 and 15 may be provided with resilient strips as shown in Fig. 4 to 10 to reduce further the transmission of noises and vibrations to the wall and window.

The compressor 32 is adapted to discharge compressed gaseous refrigerant into a discharge pipe 45 which extends to the condenser 46, the pipe being provided with a long return bend or elbow 47 which permits vibration of the compressor with respect to the condenser 46. The condenser 46 preferably comprises horizontal tubes 48 and vertical fins 49 which form a grid across the entire outer end of the unit and across which a stream of outside air is induced to flow to liquefy the refrigerant in the condenser. The liquid refrigerant then passes through a liquid line 50 which extends through the partition 25 into the evaporating compartment 21, being attached therein to a dehydrating device 51 of any suitable character and communicating with a capillary tube expansion device 52. Other expansion devices may be used, the purpose thereof being to permit the expansion of a controlled amount of refrigerant into the evaporator coil 55 which preferably comprises horizontal tubes 56 and vertical fins 57 forming a grid extending across most of the front of the unit and across which a stream of air to be conditioned is induced. The refrigerant then returns to the compressor through suction pipe 60 which is provided with a return bend or loop 61 permitting vibration of the compressor with respect to the evaporator.

Moisture which will be condensed by the evaporator coil 55 is preferably collected in a moisture collecting pan 65 provided with a drain connection 66 which may be connected through a resilient connecting tube 67 to a drain pipe 68 extending through partition 25 into the condensing compartment wherein it is connected, through a resilient connecting tube 69, to a moisture disposal pan 70 located adjacent the condenser 46.

A propeller, or blower of the propeller type, 75 is mounted upon and connected to the outer end of the double-ended shaft 34, and the propeller is positioned within a substantially cylindrical shroud 76 which is mounted in the pan 70 with a segment thereof below the surface of the water which may accumulate therein. Water which gathers on the surface of the shroud 76 is whipped into a spray by the action of the propeller and evaporated in the outgoing stream of air so as to dispose of the moisture without causing any to drip or run down the outside of the building. The shroud may be provided with drain openings 77 adjacent its inner or entering edge to prevent moisture from running out of the pan 70. The function and operation of the moisture disposal system is more fully explained in the copending application of Jerry M. Gruitch, Serial No. 304,018, filed concurrently herewith.

The inner end of the double-ended shaft 34 is provided with a pulley 80 which is located closely adjacent the motor housing and drives a belt 81 which extends about the inner sheave

of a double sheave flywheel pulley 82 mounted on and fixed to the crankshaft 35 of the compressor so that the compressor is driven at substantially the same speed as the motor, particularly if the operating diameter of pulley 80 and the inner sheave of pulley 82 are the same or substantially the same. The outer sheave of pulley 82 drives a belt 83 which extends about a pulley 84 of large diameter which is mounted upon, but rotatable with respect to, the extremity of the inner end of shaft 34, the pulley being provided with suitable bearings journaling the pulley on the shaft for rotation with respect thereto. The bearings are preferably spaced so as to leave an internal pocket 85 which may be packed with a lubricating medium and the pulley is preferably retained on the end of the shaft by a suitable bolt 86. The pulley 84 is preferably of large diameter so that the evaporator blower 87 which is fixed thereto by bolts 88 connecting the central portion of the blower to a hub portion of the pulley rotates at a materially reduced speed and in the same direction as the shaft 34.

25 The partition 25 adjacent which the pulley 84 is located is provided with an opening 90, preferably of fairly large diameter so that a large hub portion 91 of the pulley 84 may pass therethrough with suitable clearance. The large hub 30 provides a firm support for the blower 87 which is located in the evaporating compartment 21 and in an involute shroud 92 mounted in the evaporating compartment. The clearance space between the edge of the opening 90 and the outer surface of the hub portion 91 may be blocked against air flow by a substantially circular piece 95 of felt or other substantially impervious material of sufficient rigidity to maintain its shape, the inner edge of the felt piece 35 being depressed inwardly when the hub portion 91 of the pulley 84 is passed through the opening 90 so as to form a seal preventing the flow of hot air from the condensing compartment into the evaporating compartment.

40 45 The propeller 75, operating at high speed and being of the character disclosed, may create a substantially high pitched or loud noise, which being directed outward is not of any great annoyance to the user of the unit. The propeller 75 induces a stream of air to flow in through the right end of condenser 46, across the surfaces of compressor 32 and motor 34, and outward through the left end of condenser 46. The evaporator blower 87 induces a flow of air 50 through the left end of evaporator 55 and outward through the right end of evaporator 55 into the room through an ornamental grill 100. An entrance shroud 101 may be provided to direct the incoming airstream into the involute blower shroud 92 and the outgoing stream may be confined by transverse baffles 102 and 103 in the evaporating compartment. The evaporator blower 87 is preferably of the wheel type, as disclosed, since such blowers are more quiet than propeller type blowers. However, even such a blower, at the high speed of operation of the motor and compressor, would produce considerable noise. Therefore, the ratio of pulley 80 to pulley 84 is preferably selected so as to operate the blower 87 at a relatively slow speed, and the blower is of relatively large size so as to produce a sufficient volume of air at a low speed.

55 60 The room may be ventilated by opening an exhaust door 105 located in a wall of the unit in the space between the side wing 22 and the

partition 25, opening of the door 105 serving to cause propeller 75 to draw air from the room. The size of the door 105 is preferably selected so that the unrestricted flow therethrough does not reduce the flow of air through the right end of condenser 46 more than fifty percent in order that continued air flow across the condenser surface will continue to condense the refrigerant. The reduction in air volume across the right end of the condenser is compensated for by the lower temperature of the air passing through the exhaust door, which traverses the left end of the condenser on its way out of the unit.

It is apparent from the foregoing specification that the operation of the unit may be considerably varied by the proper selection of pulley ratios and blower and propeller sizes. I prefer to use ratios substantially as shown and described, but it is obvious that the same mechanical structure may be utilized with other ratios of pulley and blower or in other types of units. Any such modification or alteration as comes within the scope of the following claims are considered a part of my invention.

I claim:

1. An air conditioning unit comprising a partition dividing the unit into a first compartment and a second compartment, a motor, a compressor and a refrigerant condenser in said first compartment, an evaporator in said second compartment, said compressor, condenser and evaporator being connected in refrigerant flow relationship, said motor having a double ended shaft and being so placed as to have its shaft substantially normal to said partition, a condenser blower mounted on and connected to the end of said shaft farthest from said partition, a driving pulley fixed to the other end of shaft and through which the extremity of said shaft projects, a double sheave pulley drivingly fixed to said compressor, belt means connecting said driving pulley and said double sheave pulley, a driven pulley journaled on the extremity of said shaft adjacent said driving pulley, said partition being provided with an opening through which a hub portion of said driven pulley projects into said second compartment, an evaporator blower fixed to said hub portion, and other belt means connecting said driven pulley and said double sheave pulley for rotating said evaporator blower at a different speed than that of the shaft.

2. An air conditioning unit comprising a partition dividing the unit into a first compartment and a second compartment, a motor, a compressor and a refrigerant condenser in said first compartment, an evaporator in said second compartment, said compressor, condenser and evaporator being connected in refrigerant flow relationship, said motor having a double ended shaft and being so placed as to have its shaft substantially normal to said partition, a condenser blower mounted on and connected to the end of said shaft farthest from said partition, a driving pulley fixed to the other end of shaft and through which the extremity of said shaft projects, a double sheave pulley drivingly fixed to said compressor, belt means connecting said driving pulley and said double sheave pulley, a driven pulley journaled on the extremity of said shaft adjacent said driving pulley, said partition being provided with an opening through which a hub portion of said driven pulley projects into said second compartment, an evaporator blower fixed to said hub portion, and other belt means connecting said driven pulley and said double sheave

pulley for rotating said evaporator blower at a different speed than that of the shaft, the ratios of said pulleys with respect to each other being such as to drive said evaporator blower at a relatively low speed with respect to the speed of said condenser blower.

3. An air conditioning unit comprising a partition dividing the unit into a first compartment and a second compartment, a motor, a compressor and a refrigerant condenser in said first compartment, an evaporator in said second compartment, said compressor, condenser and evaporator being connected in refrigerant flow relationship, said motor having its shaft so oriented as to be substantially normal to said partition, a driving pulley fixed to an end of said shaft adjacent said partition and through which the extremity of said shaft projects, a double sheave pulley drivingly fixed to said compressor, belt means connecting said driving pulley and said double sheave pulley, a driven pulley journaled on the extremity of said shaft adjacent said driving pulley, said partition being provided with an opening through which a hub portion of said driven pulley projects into said second compartment, an evaporator blower fixed to said hub portion, and other belt means connecting said driven pulley and said double sheave pulley for rotating said evaporator blower at a different speed than that of the shaft.

4. An air conditioning unit comprising a partition dividing the unit into a first compartment and a second compartment, a motor, a compressor and a refrigerant condenser in said first compartment, an evaporator in said second compartment, said compressor, condenser and evaporator being connected in refrigerant flow relationship, said motor having its shaft so oriented as to be substantially normal to said partition, a driving pulley fixed to an end of said shaft adjacent said partition and through which the extremity of said shaft projects, a double sheave pulley drivingly fixed to said compressor, belt means connecting said driving pulley and said double sheave pulley, a driven pulley journaled on the extremity of said shaft adjacent said driving pulley, said partition being provided with an opening through which a hub portion of said driven pulley projects into said second compartment, an evaporator blower fixed to said hub portion, and other belt means connecting said driven pulley and said double sheave pulley for rotating said evaporator blower at a different speed than that of the shaft.

5. An air conditioning unit comprising a partition dividing the unit into a first compartment and a second compartment, a motor, a compressor and a refrigerant condenser in said first compartment, an evaporator in said second compartment, said compressor, condenser and evaporator being connected in refrigerant flow relationship, said motor having its shaft so oriented as to be substantially normal to said partition, a driving pulley fixed to an end of said shaft adjacent said partition and through which the extremity of said shaft projects, a double sheave pulley drivingly fixed to said compressor, belt means connecting said driving pulley and said double sheave pulley, a driven pulley journaled on the extremity of said shaft adjacent said driving pulley, said partition being provided with an opening through which a hub portion of said driven pulley projects into said second compartment, an evaporator blower fixed to said hub portion, and other belt means connecting said driven pulley and said double sheave pulley for rotating said evaporator blower at a different speed than that of the shaft, the ratios of said pulleys with respect to each other being such as to drive said evaporator blower at a relatively low speed with respect to the speed of said condenser blower.

opening through which a hub portion of said driven pulley projects into said second compartment, an evaporator blower fixed to said hub portion, and other belt means connecting said driven pulley and said double sheave pulley for rotating said evaporator blower at a different speed than that of the shaft, said driven pulley having a hub portion of large diameter providing a firm support for said evaporator blower.

6. An air conditioning unit comprising a partition dividing the unit into a first compartment and a second compartment, a motor, a compressor and a refrigerant condenser in said first compartment, an evaporator in said second compartment, said compressor, condenser and evaporator being connected in refrigerant flow relationship, said motor having its shaft so oriented as to be substantially normal to said partition, a driving pulley fixed to an end of said shaft adjacent said partition and through which the extremity of said shaft projects, a double sheave pulley driv-

ingly fixed to said compressor, belt means connecting said driving pulley and said double sheave pulley, a driven pulley journaled on the extremity of said shaft adjacent said driving pulley, said partition being provided with an opening through which a hub portion of said driven pulley projects into said second compartment, an evaporator blower fixed to said hub portion, and other belt means connecting said driven pulley and said double sheave pulley for rotating said evaporator blower at a different speed than that of the shaft, said driven pulley having a hub portion of large diameter providing a firm support for said evaporator blower and said partition having an annular piece of felt mounted thereon and overhanging the edge of said opening so as to contact the surface of said large hub portion and form therewith a seal to prevent the passage of air from one compartment to the other.
